UNITED STATES PATENT OFFICE

2,550,016

OSCILLATING APPARATUS

David F. Maners, San Francisco, Calif., assignor,
by direct and mesne assignments, to Beauty-
master, Inc., a corporation of California

Application September 3, 1947, Serial No. 771,948

7 Claims. (Cl. 250—36)

1

My invention relates to oscillators, and particularly to oscillators adapted to supply small currents at relatively low frequency to produce muscular contractions and thus give passive exercise where this is therapeutically desirable.

Among the objects of my invention are to provide equipment which is safe for home use by the patient, and because of its inexpensive construction can easily be afforded by the average family for such home use; to provide an oscillator which, because of the unusual wave forms generated thereby, produces a high degree of stimulation with relatively small voltages and currents, which are well within the limits which unskilled personnel can safely handle; to provide an oscillator the output of which is limited to such small currents and voltages, and is so isolated from the supply circuits that there is no possibility of shock from the supply circuit; and to provide a device wherein the oscillations supplied can be automatically and rhythmically interrupted at a controllable rate so that the muscular contractions produced can be timed to meet the particular requirements of the muscles to be exercised.

Considered broadly, the oscillator of my invention comprises a vacuum tube, preferably a triode, the grid and anode of which are connected respectively to the primary and secondary windings of a transformer. The other end of the primary winding is connected to a fairly high positive potential with respect to the cathode; e. g., to the opposite side of the usual 110-120 volt domestic supply. Such supply can be either D. C. or A. C., for if it be the latter the device operates on alternating half cycles, which appears to make no difference in the muscular effects produced.

The distinguishing characteristic of the circuit is that the secondary connects to the cathode without the interposition of any external supply of plate current and voltage. A resistive circuit to control the intensity of oscillation may be included in this circuit, and means may be provided for rhythmically interrupting the oscillations to give continuous exercise. The oscillating currents are applied where desired from an insulated tertiary winding on the transformer which couples the anode and grid circuits.

The invention and its mode of operation can be more clearly understood from the detailed description of a preferred embodiment which follows, together with the accompanying drawings, wherein:

Fig. 1 is a circuit diagram of the device as constructed for alternating current operation, and

Fig. 2 is a reproduction of the potential wave 55 compared to the grid circuit induces a voltage

2

produced, as displayed on the screen of a cathode ray oscilloscope with its sweep circuit synchronized with the 60-cycle supply current.

Considering first the oscillator proper, it comprises a triode 1 having an anode 3, grid 5, cathode 7 and heater 9. The heater is connected across the A. C. supply lines 11—12 through a resistor 13 (for reducing the heater current to its proper value), and a filament switch 15 may conveniently be included in this circuit. The supply lead 11 will, on occasion, hereinafter be referred to as the "positive" side of the line and the lead 12 as the "negative" side, since this relationship holds during the half cycle of the supply voltage when the oscillation occurs. The device is dead during the other half cycle.

Grid 5 connects to the positive lead 11 through the primary coil 17 of a transformer 19. A small condenser 21 (about .01 mmf.) is preferably bridged across the coil 17, since this suppresses radio interference which the oscillator otherwise may cause. The cathode 7 connects through a lead 23 to one arm 25 of a 3-pole, 3-position switch. In the position shown, where only the basic circuit of the oscillator is employed, the arm 25 contacts the switch point 27 which connects directly with the negative lead 12. The grid circuit then can be traced from the positive side of the line through the coil 17 to the grid 5, thence through the space path of the tube to the cathode, and so through lead 23, switch arm 25 and point 27 back to negative line 12.

To trace the plate circuit we may start with the negative lead 8 through the second switch arm 29 and point 31 to the lower end of the secondary winding 33 of transformer 17, the upper end of which connects to the anode 3. The anode bias potential is therefore the potential of the cathode; there is no potential in the anode circuit except what is induced from the primary of the transformer 19. The ratio of primary to secondary of the transformer is about 3:5 in the specific apparatus described, but is not critical.

The mechanism of oscillation in the active half of the cycle appears to be as follows:

The grid 5, connected to the positive side of the line, starts to draw current, thus imposing a positive potential on the end of the transformer primary 17 to which it is connected and inducing a higher positive voltage in the secondary 33 which appears on the anode. The discharge promptly transfers to the latter, and because of the amplifying characteristic of the tube and the relatively low resistance of the plate circuit as

which swings the grid toward the negative and cuts off the flow, whereupon the cycle repeats. The potential developed in the plate circuit is shown in Fig. 2. Oscillation starts when the grid reaches a critical positive potential, which occurs at about 45 electrical degrees. The build-up of potential is very rapid; after reaching a sharp peak the potential falls off with increasing rapidity to a negative peak, following which it swings again toward the positive along an approximately exponential curve until the critical initial voltage is again attained, when the action repeats. With the circuit constants as here described four complete oscillations occur in each active half cycle of the supply current, the rate of the oscillation therefore being nearly 1000 cycles per second.

The currents thus generated are applied to the patient through a tertiary coil 35 on the transformer 19. The turn ratio of this coil with respect to the primary is about 1:2 in the device described, being about 100 turns of wire on a one-half inch square core. In this embodiment the tertiary is closed through a 400 ohm potentiometer, and moist pad electrodes 39 connect to the movable contact and one end of the potentiometer respectively.

It is evident from this arrangement that the actual power that can be delivered to a patient's body is very small. The currents will not register on the thermocouple or hot wire instruments such as are available in most radio laboratories, and special sensitive instruments are necessary if they are to be measured. The voltages indicated by ordinary instruments are also small, but a peak voltmeter shows that instantaneously the voltage rises enough to explain the physiological effects. The point is that the currents which flow are always too small to cause any danger to the patient.

As thus far described the instrument produces a continuous contraction of the muscles. While this is desirable for some forms of treatment the effect of regular exercise is better produced by applying the oscillations in pulses, and the device as shown has means for producing such pulses of varying length, over two ranges, electronic means for pulsing, at rates of from about 5 per second to about 1½ seconds, and electromagnetic means for producing pulses of longer duration, say up to 5 seconds or more.

For the rapid pulses the three-pole switch is turned to connect the arm 25 with contact 41, which, being in parallel with contact 27, does not alter the grid-cathode circuit. This same position of the switch brings arm 29 into connection with contact 43, which cuts a timing circuit into series with the anode, cathode and transformer coil 33.

The timing circuit comprises a condenser 45, of the order of 50 mf. capacity, shunted by a resistor 47 of about 100,000 ohms, both in series with an adjustable resistance 49 whose maximum value may be about 250,000 ohms. The current pulses in the coil 33 are, of course, rectified. These pulses charge the condenser to a point where the oscillations are blocked, and remain so until the charge has leaked off. The rate of both charge and discharge is controlled by the rheostat 49, through the more rapid range above specified.

For longer timing the switch blades 25 and 29 are turned to contacts 51 and 53 respectively, which brings switch arm 55 in contact with a switch point 57, this latter arm having been on

unconnected points in the switch positions previously described. In this last switch position the timing circuit is shorted out by the switch arm 29, leaving the anode circuit as first described, and pulsing is accomplished by periodically opening and closing the grid-cathode circuit.

The latter circuit can now be traced from line 11 to the grid 5 and the space path to cathode 7, thence through arm 25 and contact 51 to a lead 59 which connects to lower contact 61 of a relay 63, and so back through lead 65 and switch arm 29 to the negative line 12.

The relay is actuated by a side circuit which, starting from lead 11 and switch arm 55, continues through a lead 67 to the anode 69 of a diode rectifier 71, through the space path to the cathode 73, and then through the center tap of filament transformer 75 through the relay coil and back to line 65. The primary of the filament transformer is excited through a branch circuit from line 61 to relay contact 77 and the relay armature to line 65. The contacts may be bridged by a condenser 79 and resistor 81 to suppress radio interference.

The timing of the relay operation is controlled by a condenser 83 in series with a high resistance rheostat 85, shunted across the winding of relay 63. When the diode is first excited the rectified current it passes first goes to charge condenser 83 rather than passing through the relay coil. As the condenser becomes charged, however, an increasing amount of current passes through the coil until finally the relay operates, closing contact 61 and exciting the oscillator circuit, and at the same time opening the filament transformer circuit of diode 71. The latter then ceases to rectify as the cathode cools, condenser 83 loses its charge and the relay releases, starting the cycle over again. The length of the relay cycle is controlled by the rheostat 85.

It will be clear that pulses of as long duration as those obtained by the relay circuit just described could be obtained by increasing the time-constant of circuit 45-47-49 and also that other methods of pulsing can be used with the oscillator of my invention. For certain purposes therapeutists appear to prefer the sudden stopping and starting of the oscillations obtained by the relay pulsing rather than the more gradual waxing and waning provided by the time constant circuit. I do not wish to be limited to any specific method of pulsing the oscillator here disclosed, nor are the circuit constants mentioned in the description to be considered as more than merely illustrative, since they can be varied over a wide range. I desire to be limited in my protection on this invention only as limitations are expressed in the following claims.

I claim:

1. An oscillator comprising a vacuum tube having an anode, a cathode and a grid, a circuit connected to apply a positive potential to said grid with respect to said cathode, a transformer having a primary winding connected from said grid to said cathode through said circuit, and a step up secondary winding connected from said anode to said cathode to maintain said anode and cathode at the same mean potential and to induce on said anode a positive potential upon increase of current in said primary winding, and means for applying oscillating potentials developed by said transformer windings to a load circuit.

2. An oscillator in accordance with claim 1 including a resistive timing circuit in series with said secondary winding.

3. An oscillator in accordance with claim 1 including a resistor-capacitor circuit of variable time constant in series with said secondary winding.

4. An oscillator in accordance with claim 1 wherein the final means mentioned therein comprises a tertiary winding isolated from the primary and secondary windings thereof.

5. A device for passively exercising muscles by electrically stimulated contractions comprising an oscillator in accordance with claim 1 and means for regularly and periodically interrupting the oscillations thereof at a controllable rate.

6. A device for passively exercising muscles by electrically stimulated contractions comprising an oscillator in accordance with claim 1 and means for periodically opening the circuit connecting the cathode and the grid at a controllable rate.

7. A device for passively exercising muscles by electrically stimulated contractions comprising

10

15
